ELEVATOR SYSTEM

Harold V. McCormick, Evanston, Ill., assignor to
Westinghouse Electric Elevator Company, a
corporation of Illinois

Application February 6, 1932. Serial No. 591,378

9 Claims. (Cl. 187—29)

My invention relates to elevator systems in which the hatchway doors at the floor landings must be closed and mechanically locked when the cars are not making stops at such landings.

5 One object of my invention is to prevent any unsafe operation of an elevator car after any one of the hatchway doors associated with it is unlocked.

Another object of my invention is to provide 10 an elevator system in which the deceleration of an elevator car to a stop, the unlocking and opening of the hatchway door when the car has decelerated to within a few inches of the stop, and the final stopping of the car level with the

15 floor may be followed by a disablement of the elevator control system to prevent further operation of the car until the hatchway door is reclosed and mechanically locked in its closed position.

20 Further objects of my invention will in part be obvious, and will in part appear hereinafter.

For an illustration of one of the various forms my invention may take, reference may be had to the accompanying drawings in which:

25 Figure 1 is a view in elevation of the interior of an elevator hatchway illustrating the hatchway doors and also illustrating, in section, an elevator car disposed in the hatchway;

Fig. 2 is an enlarged view, in side elevation, 30 of the means for locking the hatchway doors shown in Fig. 1;

Fig. 3 is an enlarged view in front elevation showing the hatchway door lock with its cover removed, and

35 Fig. 4 is a diagrammatic representation of the elevator system for operating the car and the doors in the hatchway shown in Fig. 1.

Referring more particularly to the drawings, I have illustrated therein an elevator car C suitably suspended in a hatchway 8 by a cable Ca which passes over a hoisting drum D to a suitable counterweight Cw. The hoisting drum D is directly coupled to, and operated by, the armature EM' of an elevator driving motor EM.

45 The control system for the driving motor EM is illustrated as being of the variable voltage type wherein the armature EM' of the motor is connected in loop-circuit with the armature G' of a generator G. The generator G is provided with a separately excited field winding GF and a series field winding ESF. The armature G' of the generator G is suitably driven by means of a motor M illustrated as a shunt wound type having its armature M' and a field winding MF connected in shunt relation to a source of power

designated by the supply conductors L1 and L2.

The direction and speed of operation of the motor EM is suitably controlled by controlling the direction and value of the excitation current supplied to the separately excited field winding 60 GF of the generator G.

The direction of the excitation current for the field current GF is suitably controlled by means of an "up" direction switch 1 and a "down" direction switch 2, while the value of the current supplied to the field winding GF is controlled by means of an intermediate speed relay 3 and a high speed relay 4.

A brake 9 is provided for preventing rotation of the hoisting drum D when the hoisting motor 70 is not in operation. The brake 9 is controlled by a brake magnet 10 which is connected in series with the coils of the direction switches in such manner that it will be deenergized to permit the application of the brake 9 when the direction switches are deenergized to stop the car.

A car switch CS is mounted in the elevator car C to be actuated by the attendant on the car for controlling the operation of the direction switches 1 and 2 and the speed relays 3 and 4 to move the car as desired.

A control system of any suitable type may be employed for automatically stopping the car C level with the floors past which it moves when the car switch CS is moved to its central or car 85 stopping position. As a suitable system of control, I have illustrated a system of the automatic inductor landing type which is disclosed in the copending application of E. M. Bouton, Serial No. 731,921, filed August 14, 1924, and assigned to the Westinghouse Electric & Manufacturing Company.

The inductor landing system includes an "up" high speed inductor relay HU and an "up" intermediate speed relay SU for causing the car 95 to be automatically decelerated from its high and intermediate speeds, respectively; and a stopping inductor relay S for automatically bringing the decelerated car to a stop at an exact level with the floor when the car is travelling upwardly. Similarly, a "down" high speed inductor relay HD, a "down" intermediate speed relay SD and the automatically stopping relay S will cause the car to slow down and stop at the floors when it is travelling downwardly.

In this system, each of the floor landings past which the car moves should be provided with a set of inductor plates for cooperation with the inductor relays as the car approaches predetermined points in advance of the landings to cause 110

the car to stop thereat, when the car switch is centered for a stop.

The inductor plates for one floor landing are illustrated as comprising an "up" high speed inductor plate HU', an "up" intermediate speed inductor plate SU', and a stopping inductor plate S' for successively operating the inductor relays HU, SU and S when the car, moving upwardly, approaches the floor level at which the inductor plates are disposed.

When the car is travelling downwardly, the high speed inductor plate HD', the intermediate speed inductor plate SD' and the stopping inductor plate S' will successively operate the inductor relays HD, SD and S, respectively, as the car approaches the floor landing at which the plates are disposed, to decelerate the car and stop it at the landing.

As shown in Fig. 1, the hatchway 8 is provided with a hatchway door comprising a pair of slidable panels 11 and 12. The door panels 11 and 12 are operably connected by means of a pair of racks 13 and 14 and a pinion 15 in such manner that movement of panel 12 to an open or to a closed position will cause the panel 11 to also move to its open or to its closed position.

The means for operating the door panels 11 and 12 comprises a pair of toggle levers 16 and 17, the inner ends of which are connected by a pivot 18 and the outer ends of which are connected respectively to the panel 12 by a pivot 19 and to the wall of the shaft by a pivot 20. A motor 22, pivotally mounted on the shaft wall 10, is connected by a plurality of levers to the toggle lever 17 in such manner that rotation of the motor in one direction will raise the toggle levers 16 and 17 to open the door panels 11 and 12, while rotation of the motor in the opposite direction will move the levers 16 and 17 to their straight line positions to close the door panels 11 and 12.

The car C (Fig. 1) is provided with a door comprising two slidably mounted panels 24 and 25 movable in opposite directions in a manner similar to the hatchway doors. The actuating mechanism for the car door differs from the actuating mechanism for the hatchway door in that it comprises two levers 26 and 27 mounted on pivots 28 and 29 stationary on the car. One end of each pivoted member is slidably connected to a panel of the car door as at 30 and 31, and the opposite ends are connected through link members 32 and 33 to diametrically opposite points on a worm wheel 34 which is driven by a motor 35. When the motor is rotated in one direction, the worm wheel 34 is rotated to move the levers 26 and 27 to open the car door and when the motor 35 is rotated in the opposite direction, the door panels are moved toward each other to close the entrance to the car.

Inasmuch as a hatchway door and a motor for operating it are located at each floor, some means must be provided for selectively connecting the hatchway door motor at the floor at which a stop is to be made to a circuit through which it may be operated. To accomplish this purpose, a relay switch RS is located at each floor to be closed by an inductor relay IR when the car is to make a stop at that floor. The inductor relay IR is carried on the car in such position that it will come opposite the inductor plate RS' of the relay switch as the car approaches the level of the floor at which it is to stop.

The inductor relay IR is provided with an

energizing coil which is connected to the control system through deenergization of the high speed relay 4 whenever the car is decelerated to make a stop, as shown in Fig. 1. Thus it is seen that the inductor relay will be energized to operate the relay switch at a floor only when the car is to stop at that floor.

The direction of operation of the door operating motors 22 and 35 is controlled by door opening relay O and a door closing relay C. A door operating relay 45 is provided for controlling the opening and closing relays O and C. When the door relay 45 is deenergized, the car door and the corresponding hatchway door open. When the door relay 45 is energized, the car and the hatchway door open a pair of car door contact segments. A pair of door contact segments b and c are so disposed on the car switch CS and so connected to the coil of the door operating relay 45 that that relay will be deenergized when the car switch is moved to stop the car and energized when the switch is moved to start the car.

A pair of suitable limit switches LS and LS' are provided for disconnecting the door motors from their source of electrical energy when the doors reach their fully open or fully closed position.

Inasmuch as the system for operating the car door motor and the hatchway door motor is fully illustrated and described in a copending application, Serial No. 420,092, filed January 11, 1936, a further detailed description of the system will not be given.

A door protective relay 41 and a time element door protective relay 48 are also associated with the door operating relay 45 for further controlling its operation under certain conditions to be hereinafter described.

In order that the hatchway door panels 11 and 12 may be positively locked in their closed position, and arm 39 is pivotally attached at its upper end by a pin 40 to the door operating toggle lever 17. To the lower end of the arm 39 is firmly connected a shaft 42, the lower end of which is connected by a swivel joint 43 to the upper end of a square rod 44 which extends downwardly through a square opening 46 in a lock basing 47 in such manner that the rod will be moved up or down in the casing when the toggle lever 17 moves up or down in opening or closing the door.

A notch 50 is cut in the right hand side of the lower portion of the square rod 44 in such manner that a latch 51 may rest therein when the rod is in its lowermost position by reason of the hatchway door being in its closed position. As shown, the lower end of the latch 51 impinges against the lower face of the notch 50 in such manner that the square rod 44 cannot move upwardly to permit opening of the hatchway doors unless the latch is withdrawn. The latch 51 is pivotally mounted in the lock casing by means of a bolt or pin 52 and is provided with a right hand arm 53 and a left hand arm 55.

The arm 53 of the latch extends under and acts as the armature of an electromagnet 54 that is mounted, by means of a bolt, upon a bracket 56 which constitutes a portion of the lock casing 47. When the electromagnet 54 is energized, it actuates the armature 53 to withdraw the latch 51 from the notch 50 and thereby permits the square rod 44 to move upward-

ly when the toggle lever 17 is moved to open the hatchway door panels 11 and 12.

The electromagnet 54 is connected in a circuit that extends through the contact members *a* of the relay switch RS at each floor landing in such manner that when the car stops at a landing, and the inductor relay IR energizes the relay switch RS at that landing, the electromagnet will be energized to raise the armature 53 and thereby remove the latch 51 from the notch 50 and the square rod 44.

The left hand arm 55 of the latch 51 extends past a keyhole 59 in the wall of the shaft in such manner that a key 60 may be inserted in the shaft and turned to depress the arm and thereby move the latch 51 out of the notch 50, thereby providing a means whereby the door may be unlocked in case of an emergency.

A switch 62 comprising a pair of contact members *a* and *b* is connected to the underside of the armature 53 in such manner that the switch will be opened when the door is unlocked and will be closed when the door is locked. The contact members *a* are secured to the underside 25 of the armature 53 by means of a suitable bolt and are disposed in such position as to cooperate with the contact members *b*, which are mounted, by means of bolts 64, in a bracket 65 disposed on the lock-casing 47. The lower portions of 30 the bolts 64 are constructed to serve as the binding posts to which the electric conductors controlled by the switch may be attached.

The lock-casing 47 is firmly secured, by suitable bolts 49, to the upper portion of the casing 35 of the door motor 22, which in turn, is firmly secured to the wall 8 of the hatchway.

The switch 62 controls the operations of the door protective relay 41 in such manner that, when the hatchway door is unlocked, it will be 40 moved to its open position and a gap in the car control circuit will be opened, after a predetermined period, to prevent further operation of the car until the hatchway door is reclosed and locked.

45 The invention may be best understood from an assumed operation of the system.

Assuming that the car C is standing at a floor with the doors open and that the car attendant, desiring to move the car upwardly, moves the 50 car switch CS in a counter-clockwise direction; then the contact member *b* on the car switch engages the cooperating contact member *c* to complete a circuit for energizing the relay 45 to effect the closing of the car door and the 55 hatchway door, which circuit extends from the supply conductor L1 through conductor 70, junction point 71, conductor 72, the contact members *a* of relay 48, conductor 73, junction point 74, conductor 75, the coil of relay 45, conductors 76 and 77, the contact members *c* and *b* of car switch CS, and conductor 78 to supply conductor L2.

The energization of the relay 45 closes its 60 contact members *a* thereby energizing the door closing relay C through a circuit extending from the supply conductor L1 through conductor 80, the coil of relay C, conductor 81, limit switch LS', conductor 82, the contact members *a* of relay 45, and conductors 83 and 84 to supply 65 conductor L2.

The energization of the closing relay C completes a circuit for operating the car door motor 35 and the hatch door motor 22 to close the doors, which circuit extends from supply conductor L1 through conductor 86 to junction 75

point 87; where it divides, one branch extending through conductor 88, the field of the car door motor 35 to junction point 89, and the other branch extending from the junction point 87 through conductors 90 and 91, the contact members *b* of switch RS, the field of the hatchway door motor 22 and conductors 92 and 93 to the junction point 89, thus placing both fields in parallel relation. From the junction point 89, the circuit extends through conductors 94 and 95, the contact members *a* of relay C, and conductor 96 to the junction point 97, where it again divides, one branch extending through conductor 98, the armature of car door motor 35 to the junction point 99; and the other branch extending from the junction point 97 through conductors 100 and 101, the contact members *c* of switch RS, the armature of hatchway door motor 22 and conductors 102 and 103 to the junction point 99. Thus the armatures of both motors are connected in parallel with each other and in series with the fields. From the junction point 99, the circuit extends through conductors 104 and 105, the contact members *b* of relay C and conductor 106 to the supply conductor L2. The energization of the car door motor 35 rotates the worm wheel 34 to operate the levers 26 and 27 to close the car door.

The energization of the hatchway door motor 22 causes it to straighten out the toggle levers 16 and 17, thus moving the hatchway door panels 11 and 12 to their closed position.

Inasmuch as the square rod 44 in the mechanical lock is connected to the toggle lever 110 17, the closing movement of the toggle lever pushes the square rod downwardly through the lock-casing 47 and, as the door comes to its fully closed position, the latch 51 drops into the notch 50, thereby locking the hatchway 115 door in its closed position.

The movement of the latch 51 into its locking position and the notch 50 also causes the contact members *a* and *b* of the switch 62 to close, thereby completing a circuit to energize the 120 door protective relay 41 for the purpose of rendering the car control circuit effective to permit operation of the car and also for the purpose of preventing operation of the door opening relay to the doors while the car is running. The 125 circuit for relay 41 extends from the supply conductor L1 through conductor 108, switch 62, conductor 109, the contact members of switch 62', conductor 110, the coil of relay 41 and conductor 111 to supply conductor L2. 130

The closing of the contact members *a* on the energized relay 41 completes a circuit for energizing the time element door protective relay 48 extending from supply conductor L1 through conductor 70, junction point 71, conductor 113, the contact members *a* of relay 41, conductor 114, the coil of relay 48, and conductors 115 and 111 to supply conductor L2. 135

The closing of the contact members *b* of the energized relay 48 closes a safety gap in the 140 car control system rendering it effective to permit operation of the car now that the hatchway door is closed and locked.

Returning now to the energization of relay 41, the closing of its contact members *b* and 145 its contact members *c* complete a circuit for the door operating relay 45 which will cause that relay to be maintained in its door closing position until the hatchway door is unlocked, regardless of the position of the car switch or 150

other portions of the system. This circuit extends from the supply conductor L1 through conductors 70 and 113, the contact members b of relay 41, conductors 79 and 75, the coil of relay 45, conductors 76 and 85, the contact members c of relay 41 and conductors 106, 115 and 111 to supply conductor L2.

The opening of the contact members d of the energized relay 41 adds a safety factor in preventing the completion of the circuit of the door opening relay O and the consequent operation of the door motors until the hatchway door is unlocked.

As the car attendant moves the car switch CS further in a counter-clockwise direction, the contact member a of that switch engages a cooperating contact member d and thereby completes a circuit for energizing the "up" direction switch 1 to effect the upward operation of the car. This circuit extends from supply conductor L1 through conductors 70 and 116, contact members a and d of the car switch CS, conductor 117, the coil of "up" direction switch 1, conductors 118 and 119, the coil of brake relay 10, conductor 120, the contact members b of relay 48 and conductors 121 and 122 to supply conductor L2.

The energization of the brake relay 10 releases the brake 9 and permits the operation of the hoisting drum D.

The closing of the contact members a of "up" direction switch 1 completes a self-holding circuit for the coil of that switch which extends from supply conductor L1, through conductors 70 and 124, the contact members of inductors relay S, conductors 125 and 126, the contact member a of switch 1, the coil of switch 1 and thence to supply conductor L2, as previously described.

The closing of the contact members b and c of "up" direction switch 1 energizes the auxiliary field winding GF of the generator G to operate the driving motor EM to move the car upward. This circuit extends from supply conductor L1 through conductor 128, the contact members b of switch 1, conductor 129, field winding GF, conductors 130 and 131, the contact members c of switch 1, conductor 132, resistors R1 and R2 and conductor 133 to supply conductor L2.

A still further movement of the car switch CS causes its contact member a to engage its cooperating contact member e thereby energizing the intermediate speed relay 3 to increase the speed of the car. This circuit extends from supply conductor L1 through conductors 70 and 116, the contact members a and e of car switch CS, conductor 135, the coil of relay 3 and conductors 136 and 137 to supply conductor L2.

The closing of the contact members a of the energized speed relay 3 completes a self-holding circuit for that relay extending from supply conductor L1 through conductors 70 and 139, the contact members of inductor relays SD and SU, conductor 140, the contact members a and the coil of relay 3 and conductors 136 and 137 to supply conductors L2.

The closing of the contact members b of the relay 3 shunt the resistor R1 from the circuit of the field winding GF and thereby causes the speed of the car to be increased.

Assuming now that the car attendant moves the car switch still further to its high speed position, then the high speed relay 4 will be ener-

gized to increase the speed of the car. This circuit extends from supply conductor L1 through conductors 70 and 116, the contact members a and f of the car switch CS, conductor 142, the coil of relay 4 and conductors 143 and 137 to the supply conductor L2.

The closing of the contact members a of the energized relay 4 completes a self-holding circuit for that relay extending from the supply conductor L1 through conductors 70 and 143, the contact members of high speed inductor relays HD and HU, conductor 144, the contact members a of relay 4, conductor 145, the coil of relay 4 and conductors 143 and 137 to supply conductor L2.

The closing of the contact members b of relay 4 shunts the resistor R2 from the circuit of the field winding GF, thereby still further increasing the speed of the car.

The opening of the contact members c of the relay 4 prevents any energization of the inductor relay IR on the car to unlock and operate the hatchway doors until the high speed relay 4 is again deenergized to decelerate the car to a stop.

Assuming now that the car attendant, desiring to stop the car at a floor on its upward travel, moves the car switch to its center position, then the car stopping inductor relays on the car are energized to effect the deceleration and stopping of the car through a circuit extending from the supply conductor L1 through conductors 70 and 116, the contact members a and g of the car switch, conductor 147, and thence in parallel through the coils of the inductor relays HU, SU and S and conductors 148 and 122 to the supply conductor L2.

As the car approaches the next landing, the energized inductor relay HU passes the inductor plate HU' and is operated thereby to open its contact members, thereby deenergizing the high speed relay 4 and thus causing the resistor R2 to be reinserted in the circuit previously described for the generator field GF to decelerate the car to its intermediate speed.

As the car continues its approach to the landing, the energized inductor relay SU passes the inductor plate SU' and is operated thereby to open its contact members to deenergize the intermediate speed relay 3. The opening of the contact members b on the intermediate speed relay 3 reinserts the resistor R1 in the circuit for the field winding GF and thereby decelerates the car to its low speed.

Returning now to the deenergization of the high speed relay 4, that operation closed its contact members c and thereby completed a circuit for energizing the inductor relay IR on the car for operating the movable switch RS at the floor landing. This circuit extends from supply conductor L1 through conductors 86 and 151, the coil of inductor relay IR, conductor 152, the contact members c of relay 4, and conductors 153 and 133 to the supply conductor L2. As the car approaches to within a short distance, say eight or ten inches of the floor level, the energized inductor relay IR on the car comes opposite the inductor plate RS' on the movable switch RS, and thereby pulls the switch to its closed position.

The closing of the contact members a of the movable switch RS completes a circuit for energizing the electromagnet 54 to pull up the armature 53 and thereby unlock the hatchway door at the floor at which the car is decelerating to

5 a stop. This circuit extends from the supply conductor L1 through conductors 70 and 154, the coil of electromagnet 54, the contact members *a* of switch RS, conductor 155, the contact members *h* and *b* on the car switch and conductors 78 and 122 to the supply conductor L2.

10 The first upward movement of the armature 53 opens the contact members of the switch 62 to deenergize the door protective relay 41 which opens its contact members *a*, *b* and *c* and closes its contact members *d*.

15 The continued upward movement of the armature 53 withdraws the latch 51 from the notch 50 of the square rod 44 and thereby unlocks the hatchway door.

20 In the meantime, the opening of the contact members *a* of the deenergized relay 41 has deenergized the time element door protective relay 48 to open the contact members *b* of that relay. However, relay 48 is provided with a dashpot 157 which operates to prevent the opening of the contact members *b* of relay 48 until after the expiration of a predetermined period of time, which should be so selected as to give the elevator car sufficient time to level into the floor at which it is stopping before the contact members *b* open.

25 The opening of the contact members *b* of the deenergized relay 41 deenergizes the door operating relay 45 to close its contact members *b* and thereby complete a circuit for energizing the door opening relay O to effect the opening of the car door and the hatchway door, which circuit extends from supply conductor L1 through conductor 80, the coil of relay O, conductor 158, limit switch LS, conductor 159, the contact members *d* of relay 41, conductor 160, the contact members *b* of relay 45 and conductor 84 to the supply conductor L2. It will be noted that this circuit passes through normally closed contact members *d* on the deenergized door protective relay 41 so that the door opening relay O cannot be energized until the relay 41 is deenergized by the unlocking of the mechanical lock on the door.

30 The closing of the contact members *a* and *b* on the energized door opening relay O completes a circuit for energizing the car door motor 35 and the hatchway door motor 22 in the same manner as previously described in the opening of the door except that the current through the armatures is reversed; that is, instead of passing through the junction point 97 to the junction point 99, the current now passes from the junction point 99 through the armatures to the junction point 97. The doors now move to their open positions and the motors are stopped by the operation of the limit switch LS in the usual manner. It is to be understood that the doors start to open when the car is still eight or ten inches away from the level of the landing and are in their fully-open position by the time the car comes to rest at the floor landing.

35 As the car arrives at the final stopping point, the inductor relay S comes opposite the inductor plate S' and is operated to open its contact members, thereby opening the self-holding circuit for the "up" direction switch 1 to deenergize that switch. The deenergization of the "up" direction switch 1 stops the driving motor EM and applies the brake 9 to stop the car level with the floor.

40 The delayed operation of the time element relay 48 now takes place. The closing of the contact members *a* on the relay 48 prepares a cir-

45 cuit through which the door operating relay 45 may be operated to close the doors when the car is to be started. The opening of the contact members *b* on the relay 48 opens a gap in the control circuit which makes it impossible to operate the car again until the doors are reclosed and locked.

50 Assuming now that the stop has been completed and the car attendant, desiring to continue his upward travel, again moves the car switch in the counter-clockwise direction. Then the doors will be closed and locked, the "up" direction switch 1, the intermediate speed relay 3 and the high speed relay 4 will be energized successively and will operate as previously described to cause the car to start and accelerate to its high speed.

55 Therefore, it is seen that I have provided a definite sequence of operation in decelerating the car, unlocking and opening the doors, stopping the car and thereafter rendering the control system ineffective to again start the car until the doors are reclosed and locked, and that such a definite sequence of operation will prevent unsafe operation of the elevator while the doors are unlocked.

60 I claim as my invention:

1. In an elevator system embodying a car and a motor for driving said car past a floor landing, the combination with a door, a lock for locking the door in its closed position, and means for unlocking said locking means, of means operably responsive to operation of the unlocking means for stopping the driving motor at a predetermined length of time after the unlocking of the door.

65 2. In an elevator system embodying a car and a motor for driving said car past a floor landing, the combination with a door, a lock for locking the door in its closed position, and means for unlocking said locking means, of means operably responsive to operation of the unlocking means for stopping the driving motor and means for delaying the operation of the motor stopping means for a predetermined length of time after the unlocking of the door.

70 3. In an elevator system embodying a car and a motor for driving said car past a floor landing, the combination with a control system for said motor, a door, a lock for locking said door in its closed position and means for unlocking said locking means, of means operably responsive to operation of said unlocking means for rendering said control system ineffective to operate said motor after the expiration of a predetermined length of time after the operation of said unlocking means.

75 4. In an elevator system embodying a car and a motor for driving said car past a floor landing, the combination with a control system for said motor, a door, a lock for locking said door in its closed position and means for unlocking said locking means, of means operably responsive to operation of said unlocking means for rendering said control system ineffective to operate said motor after the expiration of a predetermined length of time after the operation of said unlocking means and operably responsive to operation of the locking means to lock the door for rendering said control system effective to operate said motor.

80 5. In an elevator system embodying a car and a motor for driving said car past a floor landing, the combination with a control system for controlling said driving motor, a door, a

motor for operating said door, a lock for locking the door in its closed position, means operably responsive to the combined operation of the control system to decelerate the driving motor and the position of the car for partially completing a circuit for the door motor and for unlocking the locking means, and means operably responsive to operation of the unlocking means for completing the circuit for the door motor to open the door.

6. In an elevator system embodying a car and a motor for driving said car past a floor landing, the combination with a control system for controlling said driving motor, a door, a motor for operating said door, a lock for locking the door in its closed position, means operably responsive to the combined operation of the control system to decelerate the driving motor and the position of the car for partially completing a circuit for the door motor and for unlocking the locking means, and means operably responsive to operation of the unlocking means for completing the circuit for the door motor to open the door and for rendering said control system ineffective to operate said motor after the expiration of a predetermined length of time after the unlocking of the door.

7. In an elevator system embodying a car and a motor for driving said car past a floor landing, the combination with a control system for controlling said driving motor, a door, a motor for operating said door, a lock for locking the door in its closed position, means operably responsive to the combined operation of the control system to decelerate the driving motor and the position of the car for partially completing a circuit for the door motor and for unlocking the locking means, and means operably responsive to operation of the locking means for completing the circuit for the door motor to open the door and for rendering said control system ineffective to operate said motor after the expiration of a predetermined length of time after the unlocking of the door and responsive to the locking of the door for rendering the control system effective to operate the driving motor.

8. In an elevator system embodying a car, a motor for driving said car past a floor landing, and a door at said landing, the combination with a control system for controlling said driving motor, of a lock for locking said door in its

closed position, means operably responsive to the combined operation of the control system to decelerate the driving motor and the position of the car for partially completing a circuit for the door motor and for unlocking the lock before the car reaches the floor landing, means operably responsive to movement of the lock to its unlocking position for completing the circuit for operating the door motor to open the door before the car reaches the floor landing, means operably responsive to operation of the control system for stopping the car level with the floor landing after the door starts to open, and means operably responsive to movement of the lock to its unlocking position for rendering the control system ineffective to operate the driving motor after a sufficient length of time subsequent to the movement of the lock to its unlocking position to permit the car to be stopped level with the floor landing by the stopping means.

9. In an elevator system embodying a car, a motor for driving said car past a floor landing, a door at said landing and a motor for operating the door, the combination with a control system for controlling said driving motor, of a lock for locking said door in its closed position, means operably responsive to the combined operation of the control system to decelerate the driving motor and the position of the car for partially completing a circuit for the door motor and for unlocking the lock before the car reaches the floor landing, means operably responsive to movement of the lock to its unlocking position for completing the circuit for operating the door motor to open the door before the car reaches the floor landing, means operably responsive to operation of the control system for stopping the car level with the floor landing after the door starts to open, and means operably responsive to movement of the lock to its unlocking position for rendering the control system ineffective to operate the driving motor after a sufficient length of time subsequent to the movement of the lock to its unlocking position to permit the car to be stopped level with the floor landing by the stopping means.

10. In an elevator system embodying a car, a motor for driving said car past a floor landing, a door at said landing and a motor for operating the door, the combination with a control system for controlling said driving motor, of a lock for locking said door in its closed position, means operably responsive to the combined operation of the control system to decelerate the driving motor and the position of the car for partially completing a circuit for the door motor and for unlocking the lock before the car reaches the floor landing, means operably responsive to movement of the lock to its unlocking position for completing the circuit for operating the door motor to open the door before the car reaches the floor landing, means operably responsive to operation of the control system for stopping the car level with the floor landing after the door starts to open, and means operably responsive to movement of the lock to its unlocking position for rendering the control system ineffective to operate the driving motor after a sufficient length of time subsequent to the movement of the lock to its unlocking position to permit the car to be stopped level with the floor landing by the stopping means.
